LOUVER CONSTRUCTION

John C. Cotner, Logansport, Ind., assignor to
L. D. Long, Charleston, S. C.

Application December 16, 1948, Serial No. 65,681

3 Claims. (Cl. 189—62)

1

My invention relates to a jalousie or louver construction for shading and weatherproofing windows, doors and similar openings.

An object of my invention is to provide a louver assembly that can be closed tightly to exclude light, rain and wind.

Another object of my invention is to provide a louver assembly that can be readily opened to admit light and air.

Another object of my invention is the provision of a channel bar which is pivotally connected to each of the louvers whereby when the louvers are operated to their closed position the channel bar straddles end flanges on the ends of the louver as well as the side frame bracket or flange to which the louvers are pivotally mounted.

Another object of my invention is the provision of a channel bar which cooperates with the louvers and with the flange to which the louvers are pivoted so that when the louvers are moved to their closed position the channel bar makes a tight weatherproof construction.

Another object of my invention is to provide a frame with slots and ears to register for accurate assembly in the field.

Another object of my invention is to provide a jalousie or louver construction which may be completely assembled in the field whereby all of the parts may be shipped unassembled.

Another object of my invention is the provision of a jalousie or louver construction in which the pivotal mounting members or pins may be riveted or staked in the field when assembling the construction.

Another object of my invention is the provision of louvers which are provided with longitudinally extending ribs which give strength to the louvers.

Another object of my invention is the provision of rolling one of the edges of the louvers to provide a rod-like construction on said edge, whereby the rod-like construction provides extensions for riveting the louvers to the channel bar by removing a small portion of the material next adjacent the rolled edge.

Another object of my invention is the provision of operating and locking means for adjusting the position of the louvers, whereby the louvers when adjusted to their proper position may be locked.

Other objects and a fuller understanding of my invention may be had by referring to the following description and claims, taken in conjunction with the accompanying drawing, in which:

Figure 1 is an exploded view of a jalousie or

2

louver construction embodying the features of my invention;

Figure 2 is an assembled perspective view of my jalousie or louver construction with the left-hand side frame of the construction removed to show the end view of the louvers;

Figure 3 is an enlarged view of the end view of the louvers when moved to their closed position;

10 Figure 4 is a view similar to Figure 3, but shows in addition thereto the channel bar which is pivotally connected to the louvers for actuating the same;

Figure 5 is a cross-sectional view of some of 15 the louvers taken along the line 5—5 of Figure 2 and shows in addition thereto the channel bar for operating the louvers;

Figure 6 is a side view of the channel bar only;

Figure 7 is an enlarged cross-sectional view 20 of the right-hand side frame member of my construction, and shows particularly the manner in which the louvers are pivotally connected to the side frames and the manner in which the louvers are connected to the channel bar; and

25 Figure 8 is a view similar to Figure 7 but shows the louvers moved to their closed position, which illustrates the manner in which the louvers are made waterproof to exclude light, rain and wind.

With reference to the drawing, my louver or 30 jalousie construction comprises a top frame rail 10, a bottom frame sill 11, and two side frames 12 and 13. These frame members may be made of sheet metal or any other suitable material and are arranged to be shipped in an unassembled manner and assembled in the field. As

35 illustrated, the top frame rail 10 and the bottom frame sill 11 are provided with tabs 14 which are arranged to extend through slots 15 in the side frames, after which the tabs may be bent over for locking the frame members together. The frame members may be further tightly fastened together by means of a bolt 16 which extends through openings 17 in the side frame and openings 18 in the top frame rail and the bottom frame sill. The bolt 16 may be provided with a nut 19, whereby when the bolt is turned down tight the frame assembly is rigidly held together.

40 Each of the side frames is provided with a bracket 22 which has a spaced flange 23 so that when the bracket 22 is connected to the side frame the spaced flanges 23 are disposed at a spaced distance from the side of the frames. The bracket 22 may be anchored or fastened to 45 the side frame by any suitable means such as by

spot welding whereby the bracket 22 becomes a fixed part of the side frame. The spaced flange 23 of the bracket 22 is arranged substantially parallel to the side face of the side frame and is provided with openings 25 which are in alignment with the openings 24 in the side frame. The aligned openings are arranged to receive pivot pins 33 which pivotally anchor a plurality of louvers 31 between the side frames. The ends of the louvers are provided with end flanges 32 and each pivot pin 33 is arranged to extend through an opening 30 in the end flanges 32 of the louvers. After the louvers 31 and the pivot pins 33 are assembled, the ends of the pivot pins 33 may be staked as indicated at 34 whereby they become permanently anchored in the side frame. The staking operation may be done by any suitable tool and is arranged so that the staking and assembly may be done in the field before the side frames are fastened to the framework in which the jalousie or louver construction is adapted to be mounted. The framework into which the jalousie is adapted to be mounted is illustrated by the member 26 and the side frames may be anchored thereto by wood screws 21 that extend through openings 29 in the side frame. As illustrated in Figures 7 and 8, the side frames are provided with inturned faces 27 and 28 which rest against the supporting structure in which the jalousie or louver construction is adapted to be mounted. The inturned face 27 is part of the bracket 22 so that when the side frame is anchored to the supporting structure 26 the bracket 22 becomes directly anchored to the supporting structure 26. As shown in Figures 3, 4 and 5, the upper edge of each of the louvers is rolled as at 35 to provide a rod-like construction upon the upper edge thereof. As shown in Figures 7 and 8, the end corners of the louvers are cut away at 29 to provide rolled extensions 36 in which the rolled extensions 36 function as rivets whereby the louvers may be connected to a channel bar 37 for operating the louvers simultaneously. Each end extension 36 is adapted to extend through an opening 38 after which the end may be upset or riveted by any suitable tool in the field. The rod-like rolled end of the louver provides for rendering the louver rigid in construction from end to end. The central part of the louver is provided with a V-shaped center rib 46 which also aids in strengthening the louver against bending or deformation. The lower edge of the louver when in its closed position is provided with a V-shaped lower rib 47 which also aids to strengthen the louver. As shown best in Figures 3, 4 and 5, the lower edge of the louver overlaps the top rolled edge of the next adjacent louver.

As illustrated in Figure 8, each channel bar 37 is provided with two spaced side walls 39 and 40 and these two spaced side walls straddle the spaced flange 23 and the end flanges 32 of the louvers, whereby the construction is made waterproof to exclude light, rain and wind when the louvers are closed. As shown in Figure 6, the side wall 39 of the channel bar is provided with ears 48 through which the openings 38 are provided. The side wall 40 of the channel bar is spaced away from the side frame so that as the channel bars 37 and the louvers are operated there is complete freedom from interference with the side frame. This construction is made possible by the employment of the bracket 22 which has the spaced flange 23 located at a reasonable clearance distance from the side frame. Also,

the positioning of the spaced flange 23 as a distance from the side frame makes it possible to give rigid stability to the pivot pin 33 which supports the louvers.

Attached to the lower end of the channel bars 37 are extensions 49. As illustrated, these extensions 49 are hinged connected to the lower end of the channel bars whereby when the channel bars are actuated up and down for operating the louvers the extensions are arranged to move to permit such up or down actuation of the channel bars. The hinged construction is provided by means of a pin 50 which extends through openings 53 in the channel bar and slots 54 in the extension 49. A washer 51 may be mounted over the pin 50 prior to the insertion of a cotter pin 52 for keeping the assembly together. The lower end of each extension 49 is free and when the channel bar 37 is moved downwardly the end of the bar extension 49 engages the bottom frame sill after which the extension 49 swings outwardly along with the outward movement of the channel bar 37.

The louvers are arranged to be locked in an infinite or great number of positions by means of a locking assembly which comprises a stationary bracket 55, a connecting link 59, and a knob 71. The upper end of the link 59 is adapted to be pivotally connected to a mounting plate 57 that is suitably anchored to the outside face of the channel bar 37. The mounting plate 57 is provided with ears 58 having openings 60 therein through which a pin 62 is arranged to be mounted. The pin 62 extends through openings 61 in the link 59 and the opening 60 in the ears 58, after which a cotter pin 63 is inserted through the end of the pin for holding the assembly together. The lower end of the operating link 59 is provided with a pivoted block 64 which is connected to the operating link 59 by means of a pivot pin 67 that extends through openings 65 in the lower end of the link 59 and an opening 66 in the pivoted block 64. The pivoted block 64 is provided with a threaded extension 69 onto which the knob 71 is threaded. A washer 70 may be placed between the knob 71 and the pivoted block 64. As illustrated in Figure 2, the threaded extension 69 is adapted to extend through an elongated slot 56 in the stationary bracket 55, whereby when the knob is turned tight against the stationary bracket 55 the louvers are held in a fixed position. The louvers may be moved by unloosening the knob 71 and then sliding the pivoted block up and down whereby the link 59 operates the channel bar to which it is attached for adjusting the position of the louvers, after which the knob 71 may be again retightened for holding the channel bar in a fixed position.

As will be noted from the entire description and drawing, the jalousie or louver construction may be assembled in the field whereby the entire construction may be shipped to a designation in an unassembled condition. After complete assembly, the louvers may be operated to any number of predetermined positions by the operation of the knob 71. When the louvers are operated to the closed position each channel bar 37 straddles the end flanges 32 of the louvers as well as the spaced flange 23 so that the entire construction makes a weatherproof assembly which excludes light, rain and wind.

The end flanges 32 extend laterally from the ends of the louvers and correspond in length substantially to the width of the louvers, except for the cut away notch 29 in one of the corners which

makes clearance for the rolled extension 36 riveted to the channel bar 37.

Although the invention has been described in its preferred form with a certain degree of particularity, it is understood that the present disclosure of the preferred form has been made only by way of example and that numerous changes in the details of construction and the combination and arrangement of parts may be resorted to without departing from the spirit and the scope of the invention as hereinafter claimed.

I claim as my invention:

1. In a louver construction, a frame having a side wall, a mounting flange connected to said side wall, said mounting flange having a first portion extending away from the side wall and having a second portion angularly disposed with respect to the first portion and spaced from said side wall in substantially a parallel relationship thereto, a louver having an end portion provided with a laterally extending end flange and corresponding in length substantially to the width of the louver, pivot means fastened to said end flange and extending through the second portion of said mounting flange and said side wall for pivotally fastening the end flange of the louver to said frame, said louver having a longitudinally extending edge portion terminating in a notch having a side disposed at a spaced distance inwardly of said end portion, a rod extension projecting from said side of the notch and extending toward said end portion, and a channel member pivotally mounted on said rod extension to actuate said louver to open or closed position, said channel member having side walls disposed to straddle said laterally extending end flange on the end portion of the louver and the second portion of the mounting flange when the louver is in a closed position, said channel member having a connection portion disposed for actuation, and manually operable means connected to said connection portion for actuating said channel member and the louver.

2. In a louver construction, a frame having a side wall, a mounting flange connected to said side wall, said mounting flange having a first portion extending away from the side wall and having a second portion angularly disposed with respect to the first portion and spaced from said side wall in substantially a parallel relationship thereto, a louver having an end portion provided with a laterally extending end flange and corresponding in length substantially to the width of the louver, pivot means fastened to said end flange and extending through the second portion of said mounting flange and said side wall for pivotally fastening the end flange of the louver to said frame, said louver having a longitudinally

extending edge portion terminating in a notch having a side disposed at a spaced distance inwardly of said end portion, said longitudinally extending edge portion comprising a rolled rod 5 construction extending beyond said side of the notch and providing a rod extension, and a channel member pivotally mounted on said rod extension to actuate said louver to open or closed position, said channel member having side walls disposed to straddle said laterally extending end flange on the end portion of the mounting flange when the louver is in a closed position, said channel member having a connection portion disposed for actuation, and manually operable means connected to said connection portion for actuating said channel member and the louver.

3. In a louver construction, a frame having a side wall, a mounting flange connected to said side wall, said mounting flange having a first portion extending away from the side wall and having a second portion angularly disposed with respect to the first portion and spaced from said side wall in substantially a parallel relationship thereto, a louver having an end portion provided with a laterally extending end flange and corresponding in length substantially to the width of the louver, pivot means fastened to said end flange and extending through the second portion 20 of said mounting flange and said side wall for pivotally fastening the end flange of the louver to said frame, said louver having a longitudinally extending edge portion terminating in a notch having a side disposed at a spaced distance inwardly of said end portion, a rod extension projecting from said side of the notch and extending toward said end portion, and a channel member pivotally mounted on said rod extension to actuate said louver to open or closed position, 25 said channel member having side walls disposed to straddle said laterally extending end flange on the end portion of the louver and the second portion of the mounting flange when the louver is in a closed position. 30
